(57) **CLAIM**

The ornamental design for a part of high pressure cleaner, as shown and described.

DESCRIPTION

FIG. 1 is a front, top and left side perspective view of a part of high pressure cleaner showing the new design;

FIG. 2 is a front, top and right side perspective view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a front elevational view thereof; and,

FIG. 8 is a rear elevational view thereof.

The broken line showing of various elements in FIG. 8 forms no part of the claimed design.

1 Claim, 8 Drawing Sheets(56)
